UNITED STATES PATENT OFFICE.

AUGUST KEHM, OF CHICAGO, ILLINOIS.

SUPPORT.

Application filed March 22, 1924. Serial No. 700,984.

This invention relates to supports by which pipes, cables, shafting, etc., are attached to the ceilings, walls and the like, of buildings, or other structures. Heretofore, supports of this character have included joints or connections that either limited the use of the supports or were unreliable in service because they loosened under the action of vibrations. It is, therefore, the principal object of this invention to provide a support suited to a wide range of work and one which will securely hold pipes or brackets carrying them in spite of vibrations or casual movements of any kind.

Further objects of the invention are to provide a support including an insert adapted to be easily attached to concrete forms, set between brick or stone during construction, or fixed in pockets cut in existing structures, and a simple anchorage element that will quickly and securely fasten a bolt, or the like, to the insert after the latter has been implanted; and to provide a construction that can be manufactured and used by unskilled labor, thereby effecting economy both in manufacture and installation.

Further objects and advantages of the invention will become apparent as the disclosure proceeds and the description is read in connection with the accompanying drawings illustrating a selected embodiment of the invention, and in which

Fig. 1 shows the insert nailed to the concrete form work and embedded in the concrete;

Fig. 2 shows the insert after the form work has been removed and a bolt has been secured therein by means of the anchorage element;

Fig. 3 is a sectional view taken on the line 3—3 of Fig. 2, and

Fig. 4 is a view illustrating the operation of setting the anchorage element in the socket of the insert.

The support includes an insert generally indicated by the reference numeral 10 in which an anchorage element 11 secures a bolt, or the like, 12. The insert in the preferred form here illustrated, includes a bottom or base 13 above which is a socket portion 14 that is connected by stout legs 15 with a plate or anchor 16. The plate 16 is of suitable form and dimensions to provide a strong grip on the building material, and the passage 17 between the legs permits the building material to pass entirely under the plate and form a solid connection. A convenient form is that

illustrated in which the plate has the overhanging edges 18 and the legs diverge from the socket to the plate.

For convenience in securing the insert to form work the base 13 has perforated ears 18 adapted to receive nails 19 by which the insert may be conveniently mounted in place and securely held there while the concrete is laid or the other building material is placed.

As here shown, it is preferred that the cavity in the socket portion be generally rectangular in cross section so as to cooperate with the polygonal head 20 of the bolt 12 in a well understood manner, but where more convenient the cavity may take a different form. It is not necessary that the cavity be such as to fit the head of the bolt or other fastening tightly, and it is contemplated that inserts of one size may be used in connection with bolts of different sizes but having heads too large to rotate more than part of a turn within the cavity.

The preferred anchorage element 11, here illustrated, is substantially inverted U-shaped in form prior to assembly, as indicated in Fig. 4. It may be made from bar stock of suitable strength by bending into the shape shown in Fig. 4, and perforating the upper or cross part between the legs of the U. When the pipes, or the like, are to be installed, suitable bolts are passed through the anchorage elements and the assemblies thus made are entered into the sockets of the inserts, as shown in Fig. 4, and afterwards the anchorage elements are spread or expanded as illustrated in dotted lines in that figure, to place the lower ends of the legs of the U in engagement with suitable seats in the sockets. In this preferred construction two of the walls 21 and 22 of the socket are set back, as illustrated in Figs. 1, 2 and 4, to expose seats 23 on the upper side of the base 13. Better support will be had if the feet 24 of the legs are slightly beveled so as to fit evenly along the seats 23.

The assembly will be facilitated by the use of a tool illustrated in Fig. 4, which may take the form of a rectangular piece of tubing 25 having its end walls 26 on opposite sides fairly blunt for use against the feet 24 when the bolts and anchorage elements are being entered, and the intermediate end walls 27 beveled to effect the spreading or opening of the anchorage elements, as will be clear from Fig. 4.

It is contemplated that the invention will

find its principal use in connection with concrete structures. The inserts will be nailed to the form work of the floors or the columns, or the like, before the concrete is run in. 5 After the concrete is set the forms will be wrecked and the inserts will be cast solidly in the concrete with the bases 13 exposed and presenting the openings 28 by which the bolts and anchorage elements are entered. When 10 the pipes, or the like, are to be installed, suitable bolts and anchorage elements are entered into the sockets by the aid of the tool 25, and a hammer or mallet, if necessary, and the anchorage elements are opened or spread 15 to set the feet firmly on the seats 23.

With this invention a bolt, or several bolts, may be securely connected to the concrete, or the building material and any suitable hanger or bracket may be securely mounted in 20 place with a minimum of effort. When once set in place there is no likelihood of loosening because the load, whether suspended from the ceiling or supported on the side of a column, will tend to prevent disconnection of 25 the bolt from the insert rather than permit the anchorage element to be released.

I am aware that the insert may be varied in form to suit different uses and the anchorage element may be embodied in different 30 shapes and constructions and I do not wish to be limited except as is made necessary by the prior art.

I claim as my invention:

1. In a device of the class described, the 35 combination of an insert adapted to be set into a structure so as to have one face exposed and including a socket accessible through an opening in the exposed face, seats in the socket adjacent to the opening, a bolt having a head located in the socket and a perforated anchorage element receiving said bolt and having downwardly and outwardly extended legs resting on said seats, said anchorage 40 element being separate from the insert and having been introduced through the opening and spread to rest the legs upon the seats and thereby prevent withdrawal of the bolt.

2. In a device of the class described, the 50 combination of an insert adapted to be set into a structure so as to have one face exposed and including a socket accessible through an opening in the exposed face, a seat adjacent

to said opening, a bolt projecting through the opening and having a head within the socket 55 and an anchorage element inserted through the opening and spread to engage the seat and thus secure the bolt to the insert.

3. In a device of the class described, the combination of an insert adapted to be set 60 into a structure so as to have one face exposed and including a socket accessible through an opening in the exposed face, seats on opposite sides of said opening and an upwardly arched anchorage element inserted through 65 the opening and so spread as to rest on said seats.

4. In a device of the class described, the combination of an insert adapted to be set 70 into a structure so as to have one face exposed and including a socket accessible through an opening in the exposed face, seats on opposite sides of the opening and an anchorage element inserted through the opening and having bendable legs spread to straddle the 75 opening and rest on said seats.

5. In a device of the class described, the combination of an insert adapted to be set 80 into a structure so as to have one face exposed and including a socket accessible through an opening in the exposed face, seats on opposite sides of said opening and an anchorage element comprising a perforated bar arched upwardly and having its ends resting on said seats. 85

6. In a device of the class described, an insert adapted to be set into a structure and including a perforated base and a hollow socket portion extending upwardly from the base, the hollow being of a size and shape to 90 receive a bolt head and prevent it rotating, an upwardly arched anchorage element inserted through the perforated base and spread to straddle the perforation and rest on the base at opposite sides of the perforation. 95

7. In a device of the class described, an insert adapted to be set in a structure and including a socket accessible through an opening in one face thereof, seats on opposite sides 100 of said openings and an anchorage element comprising a U-shaped bar perforated intermediate to receive a bolt and adapted to be spread to rest its ends on said seats.

AUGUST KEHM.
